UNITED STATES PATENT OFFICE.

ROBERT KIESSWETTER, OF KONIGSBERG, GERMANY.

CULTIVATOR.

Application filed January 6, 1923. Serial No. 611,095.

To all whom it may concern:

Be it known that I, ROBERT KIESSWETTER, a citizen of German Republic, residing at Konigsberg, i/Pr., Germany, have invented 5 certain new and useful Improvements in Cultivators, of which the following is a specification.

My invention relates to cultivators and more especially to a cultivator provided with 10 a revolving drum carrying movable spades, milling cutters or the like, which revolves in the direction of the driving wheels.

In cultivators of this type as hitherto used the spade or milling cutter drums must 15 be rotated at comparatively high speed which entails certain difficulties in adapting the drum to the unevenness of the ground. In disc-plough cultivators it has already been proposed to connect the driving shaft 20 with the motor car by means of a Cardan-joint transmission. However, this is possible only in very light machines operating with disc-ploughs, but in cultivators provided with spades or milling cutters, a 25 power transmission of this kind cannot be used, and a special kind of drive must be devised for the drum, which allows the shaft carrying the drum, or the drum itself to be operated reliably in every position.

30 This is attained in accordance with the present invention by connecting the drum with the cultivator frame by a universal joint arranged at the front of the drum. The drum is rotated by means of a shaft extending 35 through the hollow hub of the driving wheels, by bevel-wheels and articulated shafts, whereby not only the connection of the drum with the motor car becomes such that, with the aid of the joint, the drum can 40 adapt itself to every unevenness of the ground, but also the driving gear is apt to adjust itself correspondingly so that the drum or the shaft carrying it can always be driven uniformly and reliably.

45 This novel arrangement and combination of parts renders it possible to considerably increase the weight of the drum, or of the digging tools connected therewith, which is necessary in order to utilize the kinetic 50 energy resulting in the comparatively quick rotary motion of the drum as an auxiliary force for the efficiency and output of the cultivator. To attain the desired effect without an excessive increase of the total 55 weight of the drum, the centrifugal force is, according to another feature of my inven-

tion, increased by making the spades themselves, as well as the parts carrying them, as strong and heavy as possible. The same applies to the handles of the spades and to 60 the shaft, the intention being also, with respect to these members, to increase the weight and to have the main weight situated at the periphery of the drum. The same effect may, however, be attained by providing, according to the invention, special devices for adjusting and for fastening the spades and by employing spades of suitable shape and configuration.

65 The spades are adjusted by means of devices which render it possible to adjust the several rows of spades with respect to each other, such devices being arranged upon the shafts carrying the spades and, therefore, increasing the weight in the manner desired. 70 The spades themselves are detachably secured to the handles and are preferably provided with a lateral blade which, besides increasing the weight, serves for cutting into the soil at the side.

75 A heavy spade has a natural tendency to penetrate deeper into the soil so that on striking a stone or some other obstacle the spade or some other part might be damaged or even destroyed. This is obviated by a 80 special safety device attached to the handles of the spades, such device further increasing the weight at the periphery of the drum.

85 In the drawings affixed to this specification and forming part thereof a cultivator embodying my invention is illustrated diagrammatically by way of example. In the drawings

Figure 1 is a side elevation and
Figure 2 is a plan of the cultivator

90 Figure 3 is a side-view of the spade drum, drawn to a larger scale, and

Figure 4 is a similar view of the device for simultaneously adjusting all the spades.

95 Figures 5, 6, 7, 8 and 9 are details showing the means for adjusting each row of spades independently of the others.

Figure 9 is a front elevation of the lower broadened end of a spade handle.

Figure 10 is a like view of the spade fixed 100 to the handle, and

Figure 11 is a corresponding side elevation.

Figure 12 is a section on the line 12—12, and

110 Figure 13 is a section on the line 13—13 in Figure 10.

Referring to the drawings, the car frame is supported at its forward end on a steering wheel 2 and at its rear end on driving wheels 3. The steering wheel carries a direction indicator 4. Motion is transmitted from the motor 5 by means of a coupling (not shown) to an encased reversing gear 6, by means of which the shaft 7 may be rotated in one or the other direction. The shaft 7 carries a cog-wheel 8 meshing with a larger cog-wheel 9 fixed on a shaft 10 located below shaft 7. The shaft 10 carries near its ends chain-wheels 11 connected by chains with chain-wheels 12 secured to the hollow hub of the driving wheels 3 whereby these wheels can be turned in one or the other direction. Shaft 7 carries besides the cog-wheel 8 a chain-wheel 13 connected by a chain with a chain-wheel 14 fixed on a shaft 15 extending through the hollow hub of the driving wheels 3 and having bevel-wheels 16 secured to its ends. These wheels mesh with bevel-wheels 17 secured to articulated shafts 18 which turn the spade drum 20 by means of a bevel-wheel gearing 19. The drum 20 is shown in detail in Figure 3 and will be fully described hereafter.

The spade drum 20, or rather the frame carrying it, is supported by two lateral guide bars 22 and by a universal joint 23, as well as by a rope 24 suspended from a crane 25 so that the drum can be lifted into its position of rest by pulling the rope 24 and may be lowered into operative position by lowering said rope. The bars 22 merely serve as guides and as safety members, whereas the spade drum, owing to the provision of the universal joint 23 can adapt itself during working to the unevennesses of the ground in the longitudinal direction of the machine, as well as transversely thereto.

To secure the spade drum in raised position there are provided on the car hinges 26 which are closed or connected when the drum is lifted into its upper position (Figures 1 and 2) which is the position of rest, these hinges serving the purpose of preventing oscillations of the drum while the car is moving.

The bevel-wheel and cog-wheel gearings are preferably encased to prevent their being clogged by earth and dirt.

The spade drum is made of boiler plate and is secured to a shaft 27 extending across the frame. The plates 28 are apertured in order to reduce their weight and carry shafts 29 to which the spades 30 are attached by means of their handles 47. These latter are made as strong and heavy as possible, and the shafts 29 are also made as strong as possible so that the most of the weight lies at the periphery, as intended. In consequence thereof not only the power transmitted by the shaft is utilized directly thereby, but also the other forces arising in consequence

of the comparatively quick rotation of the drum are utilized for increasing the efficiency of the device.

The shafts 29 are preferably supported also in the middle of the drum by a rim 21⁷⁰ (Fig. 2) with staggered arms allowing the blades to be positioned, if desired, in staggered arrangement and to work the soil underneath the rim.

The shafts 29 are controlled in a well known manner in such a way that the spades are pushed into the soil always in the same position, that is to say, with the same inclination with respect to the horizontal. This is effected with the aid of an eccentric control, arms 31 connecting the shafts 29 with connecting rods 32 engaging an eccentric ring 33 which surrounds an eccentric 34 carried by the shaft 27, but not rotating with it. Owing to the ring 33 being compelled to roll on the eccentric 34, the shafts 29 are moved by means of the members 33 and 31 in such a manner that the spades 30 assume, in a certain definite succession, the various positions shown in Figure 3, as is well known in the art.

The spades can be adjusted simultaneously in one or the other direction by turning the eccentric 34. This is effected by means of a worm 35 arranged on the frame as near as possible to the spade drum, and engaging a toothed segment 36, the spindle of which has affixed to it a small lever 37 connected by a link 38 with the eccentric. According to the direction of rotation of the worm 35 the ring 33 is adjusted in one or the other direction by means of the shifting of the eccentric through the segment 36, the lever 37 and the link 38. In either case, the position of the eccentric is changed and all the spades are adjusted at the same time, irrespective of whether the machine is at rest or in operation. The eccentric can be adjusted with the aid of the guide slots shown in Figures 3 and 4.

The position of the several rows of blades relatively to each other is changed with the aid of wedges 42 (Figs. 5 and 6) connecting the arm 31 with the respective spade handle 29 and co-operating each with one or another of a plurality of grooves provided in the hub of the arm 31, the arrangement being such that the wedges can be withdrawn from a groove and the shaft can be turned as desired with respect to the arm 31, until the grooves of the two parts again coincide whereafter the wedges are re-inserted in order to re-establish the connection. To secure the wedges in position a disc 41 is arranged in front thereof and fixed by a screw 40. The wedges may extend through said disc which may be provided with slots for this purpose, the arrangement being such that the projecting heads of the wedges are applied from outside to the slotted disc 130.

which on being turned a little will carry the wedges along with it as they have been loosened by means of a pressure screw or the like.

5 In the modification illustrated in Figures 7 and 8, the wedges 42 are fixed to the sleeve 43, or made integral therewith, so that in order to alter the position of the spade with respect to the arm, i. e. to disconnect the 10 parts concerned and to connect them again after their relative position has been changed, the sleeve 43 must be withdrawn, the parts 31 and 29 turned relatively to each other and the sleeve be re-inserted and secured in its new position by suitable means.

The spades 30 attached to the drum consist of a plate 44 (Figs. 10 and 11), the lower portion of which is oblique and provided with a cutting edge. At one side of the 20 blade there is formed a plate-shaped projection 45, the vertical edge 46 of which also forms an oblique cutting edge, similar to that of the blade proper. The lowermost portion of the plate 45 projects beyond the 25 lowermost portion of the blade 44 and extends at right angles thereto; it penetrates into the soil prior to the blade and cuts off a strip of earth which is turned round by the blade so as to fall back in inverted position upon the soil previously treated and 30 turned in the same manner.

The blade or plate 44 is fixed to the handle or stem 47 in such a manner that the entire pressure exerted upon the blade is taken 35 up by the handle. The handle is, for this purpose, preferably provided with an enlarged portion 48 at its lower end and which is recessed at the front side to such an extent that the blade when being attached to 40 the stem has its upper fastening fork in contact with a projection 49 of the handle. The enlargement 48 of the handle has recesses 50 into which fit lugs 51 provided on the blade. The lugs 51 are integral with 45 the blade and bent round so as to form lateral angular members thereof. After the blade has been placed against the enlarged end 48 of the handle, it is secured thereto by simply driving wire pins through said lugs 50 51, as well as through bores provided in the body portion of the enlarged end 48. The wire pins 52 may have any desired shape as they are not subjected to any pressure whatever. To assist them in supporting the 55 plate 45, a small projection 53 is provided at the enlarged portion 48 of the blade handle (Fig. 13). The projection 53 is curved in correspondence to the curvature of the plate 45 and acts upon the latter just at 60 its curve, as shown in Fig. 13. To exchange a worn-off or damaged blade, all that is necessary is to remove the respective wire pins 52 which may have eyes to facilitate withdrawing them. Thereafter another blade is 65 attached to the handle and secured in po-

sition by wire pins. The pins cannot stick fast and are always easily removable, as they are not subjected to any pressure.

I wish it to be understood that I do not desire to be limited to the exact details of 70 construction shown and described, for obvious modifications will occur to a person skilled in the art.

I claim:—

1. A cultivator comprising a frame, a 75 rotary drum mounted thereon, shafts carried by said drum near its periphery and provided with soil working tools, arms secured to said shafts, a ring connected to said arms to rotate with said drum, and a 80 relatively stationary eccentric cooperating with said ring.

2. A cultivator comprising a frame, a rotary drum mounted thereon, shafts carried by said drum near its periphery and provided with soil working tools, arms secured to said shafts, a ring connected to said arms to rotate with said drum, a relatively stationary eccentric cooperating with said ring, and means for adjusting said eccentric in its 90 relation to said ring.

3. A cultivator comprising a frame, a rotary drum mounted thereon, shafts carried by said drum near its periphery and provided with soil working tools, arms secured 95 to said shafts, a ring connected to said arms to rotate with said drum, a relatively stationary eccentric cooperating with said ring, an adjusting lever mounted upon the frame, a link extending therefrom to said eccentric, 100 and means for actuating said lever.

4. A cultivator comprising a frame, a rotary drum mounted thereon, shafts carried by said drum near its periphery and provided with soil working tools, arms secured to said shafts, a ring connected to said arms to rotate with said drum, a relatively stationary eccentric cooperating with said ring, an adjusting lever mounted upon the frame, a link extending therefrom to 105 said eccentric, and means for actuating said lever comprising a rotatable worm and cooperating segment upon the axis of said lever.

5. A cultivator comprising a frame, a rotary drum mounted thereon, shafts carried by said drum adjacent its periphery, means for oscillating said shafts during the rotative movement of the drum, and soil working tools mounted for fixed rotative adjustment upon said shafts.

6. A cultivator comprising a frame, a rotary drum mounted thereon, shafts carried by said drum adjacent its periphery, means for oscillating said shafts in the rotative 125 movement of the drum, and soil working tools mounted for fixed rotative adjustment upon said shafts by means of inserted key entering aligned grooves in the shaft and tool handle.

- 4.
7. A cultivator comprising a frame, a rotary drum, a soil working tool having its stem portion mounted upon said drum and its free end flattened and provided with recesses at opposite sides, a tool blade having lugs adapted to enter said recesses, and means for securing said blade upon said flattened portion.
8. A cultivator comprising a frame, a rotary drum, a soil working tool having its stem portion mounted upon said drum and its free end flattened and provided with recesses at opposite sides, a tool blade having lugs adapted to enter said recesses, and means for securing said blade upon said

flattened portion comprising a pin extending through the body of the free end and said lugs.

9. A cultivator comprising a frame, a driving shaft mounted therein, a drum comprising opposite heads secured to said driving shaft, tool shafts mounted in said heads and provided with crank arms, an actuating eccentric loosely mounted upon the driving shaft, means upon the frame for retaining said eccentric against rotation, and connections from said crank arms to said eccentric.

In testimony whereof I affix my signature.
ROBERT KIESSWETTER.
